UNITED STATES PATENT OFFICE.

JOHN H. TOWERY, OF CUSHING, OKLAHOMA.

ENGINE.

1,103,634.

Specification of Letters Patent.

Patented July 14, 1914.

Application filed September 9, 1913. Serial No. 788,885.

To all whom it may concern:

Be it known that I, JOHN H. TOWERY, a citizen of the United States of America, residing at Cushing, in the county of Payne 5 and State of Oklahoma, have invented certain new and useful Improvements in Engines, of which the following is a specification, reference being had therein to the accompanying drawing.

10 This invention relates to a steam engine and the principal object of the invention is to provide an improved means for operating the valve slide so that the slide may be held stationary during a portion of the piston 15 stroke and then released and caused to move rapidly to its second position.

Another object of the invention is to provide an improved means for releasably holding the valve plate in a desired position, the 20 improved means being so constructed that the plate will be caused to jump in either direction desired.

With these and other objects in view this invention consists of certain novel combinations, constructions and arrangements of parts as will be hereinafter fully described and claimed.

This invention is illustrated in the accompanying drawings, wherein:—

30 Figure 1 is a top plan view of the engine. Fig. 2 is a longitudinal sectional view through the engine with the trigger controlling lever in its central position. Fig. 3 is a view similar to Fig. 2 with the lever moved to one side of the center. Fig. 4 is a view similar to Fig. 3 with the lever moved to the opposite side of the central position. Fig. 5 is a fragmentary view showing the mounting and operation of the lever. Fig. 40 6 is a perspective view of the plate which is actuated by the shifting lever. Fig. 7 is a transverse sectional view taken along the line 7—7 in Fig. 1. Fig. 8 is a transverse sectional view taken along the line 8—8 of Fig. 1. Fig. 9 is a fragmentary view of the frame with the valve plate removed. Fig. 45 10 is a view looking at the inner face of the valve plate. Fig. 11 is a fragmentary view of the mechanism for reciprocating the trigger tripping bar. Fig. 12 is a perspective view of the rod with which the valve plate is connected. Fig. 13 is a perspective view of one of the triggers.

In the accompanying drawings the number 55 15 indicates the base upon which the steam engine frame is mounted. This

frame comprises the longitudinally extending bar 16 which bar is provided with a longitudinally extending opening 17 positioned intermediate its length. A side bar 18 extends parallel to the bar 16 and these two bars 16 and 18 extend beyond the end of the frame 15 so that the shaft 19 can be rotatably mounted.

Cross heads 20 and 21 are mounted upon the frame 15 between the bars 16 and 18 and are provided with alined openings through which the end portions of the sliding bar 22 projects. This sliding bar 22 is provided with a side arm 23 which extends into the space between the bar 22 and side wall 18 and is pivotally connected with the pitman 24 by the pin 25. This pitman 24 extends through an opening formed in the head 20 and carries a collar 26 which is positioned in a disk 27 longitudinally mounted upon the shaft 19. Thus it will be seen that when the shaft 19 is rotated it will cause the bar 22 to reciprocate and release the trigger which will be hereinafter described.

A rod 28 has its ends slidably mounted in openings formed in the head 20 and 21 and is positioned above the triggers 29 and 30 pivotally connected with bearing blocks 31, so that the triggers 29 and 30 will be positioned in between the ends of the bars 22 and rod 28. The ends of the rod 28 are reduced to form the abutment shoulders 32 and 33 so that the triggers 29 and 30 can engage the shoulders and prevent the rod 28 from being moved until the triggers are released. A standard 34 extends from the sliding bar and is provided with an opening through which the rod 28 passes, thus preventing the standard to slide upon the rod. Springs 35 and 36 are mounted upon the rod 28 between the standard and the heads 20 and 21 and have their free ends bearing against the standard. The ends of the bar 22 are reduced thus forming abutment shoulders 37 and 38 so that these abutment shoulders can raise the triggers and release the rod 28.

A shifting lever 39 is pivotally connected with a bracing bar 40 which connects the heads 20 and 21 and is provided near its upper end with a pin 41 which fits in a notch 42 formed in the rack 43. This shifting lever extends downwardly beneath the bracing bar 40 and has its lower end pivotally connected with the upstanding central portion 44 of the strip 45. By shifting this

lever 39 from the position shown in Fig. 2 to that shown in Fig. 3 or to that shown in Fig. 4, the desired trigger can be prevented from engaging the shoulder at its end of the 5 rod 28.

The cylinder 46 is carried by the longitudinally extending bar 16 and is positioned so that the inlet ports will register with the inlet ports of this bar. The piston which 10 travels in the cylinder is connected with the piston rod 48 which piston rod has its outer end connected with the sliding block 49 which travels in the guides 50. This sliding block 49 is connected with the pitman 51 which leads to the wheel 52 and is secured thereto so that when the pitman reciprocates, the wheel will be caused to rotate. 15

A valve plate 53 is slidably connected with the longitudinally extending bar 16 20 inside the steam chest 46' by means of the bolts 54 which extend through slots 55 formed in the plate. This plate is provided with the outlet ports 56 and 57 which communicate with the chamber 58 by means of 25 the passage 59. This chamber 58 registers with a chamber 60 with which the pipe 61 communicates, and it will, therefore, be seen that the dead steam can pass into the pipe 61 through the outlet ports 56 and 57. The 30 inlet port of the cylinder communicates with the inlet port 62 so that the live steam can enter the cylinder from the steam chest. This plate is connected with the reciprocating rod 28 by means of the pin 63 which 35 passes through an opening 64 in the end of the rod and it will be seen that when the rod moves the valve plate will be moved from one position to another.

The operation of this device is as follows: 40 The engine is started and when the shifting lever is in the position shown in Fig. 2 the ends of the strip 45 will not engage either of the triggers to such an extent that it will be prevented from engaging the rod 28. As 45 the shaft 19 rotates the reciprocating bar will move and this will cause the standard to compress one of the springs until the shoulders 37 or 38 hits its trigger, thus releasing the rod and permitting it to move 50 under the impulse of the compressed spring and give the valve plate a quick movement. If it is desired to have the spring 36 compressed without the spring 35 being compressed, the shifting lever is moved to the 55 position shown in Fig. 3 and this will cause one end of the strip 45 to engage one end of the trigger 29 and swing it upon its pivot so that its upper end will not engage the shoulder 32. The spring 35 will therefore 60 not be compressed since the rod can move freely in that direction as far as necessary. If it is desired to reduce the rotation of the engine, the shifting lever is moved to the position shown in Fig. 4 in which position 65 the trigger 30 will be moved out of engage-

ment with the shoulder 33 and the trigger 29 permitted to engage the shoulder 32 and thus permit the shoulder 35 to be compressed. It will thus be seen that a device has been provided whereby the movement of 70 the valve plate can be controlled and the plate held stationary during a portion of the piston stroke and then instantly released to permit the piston to be moved rapidly to the opposite end of the cylinder. It will 75 also be seen that the rotation of the shaft 19 controls the operation of the valve guiding mechanism and that thereby the valve plate will be at all times caused to move when the engine is in the exact position required for the best results. It will also be noted that this device can be adjusted so that it will operate equally well, no matter 80 which direction the shaft is rotated.

What is claimed, is:

1. A steam engine comprising a frame, 85 said frame comprising a pair of vertical heads positioned at a spaced distance apart, a bar slidably mounted through said heads, a rod slidably mounted within said head and positioned above said bar, said rod provided with a shoulder adjacent each end portion, adjustable collars positioned upon 90 said rod adjacent said shoulders, a standard fixedly secured to said bar and slidably mounted upon said rod, springs positioned upon said rod so as to bear at one end upon said standard and at the opposite end upon one of said adjustable collars, said collars adapted to adjust the tension of said 95 springs, means for reciprocating said bar, means for releasably holding said rod in a set position, said standard adapted to compress one of said springs when said bar is moved in one direction, said bar adapted 100 to operate said last mentioned means for automatically releasing said rod whereby said rod will be moved by one of said springs for shifting a valve plate.

2. A steam engine comprising a frame, 110 said frame comprising a plurality of heads positioned at a spaced distance apart, a bar carried by said heads and slidably mounted therethrough, a vertical standard fixedly secured to said bar, a rod slidably mounted 115 upon said heads, bearing blocks fixedly secured upon each of said heads at a spaced distance apart, a plurality of triggers carried by said blocks, each trigger being pivotally secured adjacent one end portion so as to allow the larger portion thereof to extend downwardly, the short ends of said triggers adapted to alternately engage said rod for holding the same in a set position, 120 springs carried by said rod and actuated by said standard whereby said rod may be moved for operating a valve plate, means for operating said bar, said bar adapted to alternately lift the lower ends of said triggers 125 whereby the upper ends of said triggers 130

will be released from said rod for allowing said rod to operate.

3. A steam engine comprising a frame, a bar slidably carried by said frame, means 5 for operating said bar, a rod slidably mounted upon said frame, a standard fixedly secured to said bar and slidably mounted upon said rod, a spring carried by said rod and adapted to be actuated by said 10 standard whereby said rod may be moved by said spring for sliding a valve plate, triggers carried by said frame for engaging said rod for holding the same in a set posi-

tion, said bar adapted to operate said triggers for releasing said rod, and a lever pivotally secured to said standard and pivotally secured to said frame, whereby said bar may be manually shifted for moving said rod whereby the valve plate will be shifted for starting the engine. 15 20

In testimony whereof I hereunto affix my signature in presence of two witnesses.

JOHN H. TOWERY.
